CLAIM

The ornamental design for a drying rack, as shown and described.

DESCRIPTION

FIG. 1 is a front perspective view of a drying rack showing our new design;

FIG. 2 is a rear perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof; and,

FIG. 9 is a cross-sectional view thereof along cross-section line 9-9 of FIG. 3.

The broken lines illustrate unclaimed portions of the drying rack and form no part of the claimed design.

1 Claim, 6 Drawing Sheets
